[57] CLAIM

The ornamental design for a paper feeder for printer, as shown and described.

DESCRIPTION

FIG. 1 is a front elevational view of a paper feeder for printer showing our new design;

FIG. 2 is a rear view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a right, front perspective view thereof;

FIG. 8 is a right, front perspective view thereof, the broken lines showing a printer being environmental only and forming no part of the claimed design.

*FIG. 1**FIG. 2**FIG. 3*FIG. 4

FIG. 5

FIG. 6

FIG. 7

FIG. 8
